OPERATING MECHANISM

Application filed May 15, 1928. Serial No. 277,916.

This invention relates to novel mechanism for supporting and vibrating a frame, concentrator deck, or other form of separator employing vibratory movement.

Eccentrics are commonly employed as constituting a simple means for developing a vibratory movement, but many separating operations require a progressive vibratory movement. The ordinary eccentric does not produce a progressive vibratory movement and various means have been proposed heretofore for modifying the action of an eccentric to cause the same to produce a progressive vibratory movement. One of the features of the present invention pertains to this end and resides in simple means adapted to be associated with a power shaft and operable to retard the rotation of the shaft during portion of a complete rotation of the shaft and to speed up its movement during a further portion of said rotation to thereby develop a progressive vibratory movement.

It is of course necessary to support the frame to be vibrated so that it may partake of the desired vibratory movement and various forms of supporting means have been proposed to this end, but it is important that the bearings or other forms of supporting means employed be so constructed that they will not be readily injured by the dirt and dust that commonly attends separating operations. Another feature of the present invention therefore resides in yieldingly mounted bearings or rollers adapted to support the vibratory frame so that it will operate smoothly and quietly, and which are so constructed that they will not be readily injured by the dirt and dust produced by the separating operation.

In the operation of some forms of vibratory separators, such for example as certain types of concentrator decks, it is desirable to vibrate the deck transversely of its supporting frame, and another feature of the present invention resides in novel operating means for reciprocating a deck transversely of its supporting frame.

The various features of the present invention and novel combination of parts will be best understood from the following descrip-

tion when read in connection with the accompanying drawings showing good practical embodiments of the invention.

In the drawings,—

Fig. 1 is a side elevation with parts in section of a concentrator table provided with the mechanism forming the subject matter of the present invention; 55

Fig. 2 is a top plan view of mechanism shown in Fig. 1 for modifying the operation of the power shaft; 60

Fig. 3 is a top view of the operating mechanism of Fig. 1, the concentrator deck and supporting carriage being omitted;

Fig. 4 is a perspective view of the mechanism shown in Fig. 3; 65

Fig. 5 is an end view showing the material discharge end of the concentrator of Fig. 1;

Fig. 6 is a side elevation of modified means for varying the operation of the power shaft; 70

Fig. 7 is a side view of still another modification of means for varying the operation of the power shaft.

Fig. 8 is a top plan view of mechanism for vibrating the deck diagonally of its supporting base; 75

Fig. 9 is a vertical sectional view through an anti-friction bearing for supporting the deck for vibratory movement; and 80

Fig. 10 is a vertical sectional view through a modified type of anti-friction bearing for supporting the deck for vibratory movement.

The various features of the present invention are shown as associated with a concentrator table employing a deck that vibrates transversely of its supporting structure, but it will be understood that the features of the present invention are not limited in their application to concentrator decks, but may be employed in connection with various forms of frames or separators employing a vibratory movement. 85

The table concentrator illustrated in the drawings is provided with a vibratory frame or carriage 10 which is mounted upon a casing or supporting structure formed of the uprights 11 to which the longitudinally extending beams 12 are secured and the uprights are connected by the transversely extending braces 13. The concentrator deck in the pres- 90
95
100

ent case is supported so that it slopes downwardly in the direction in which the materials travel lengthwise of the deck, and to this end the supporting structure slopes downwardly from its left to its right-hand end, as clearly shown in Fig. 1.

The concentrator deck illustrated is constructed to be vibrated transversely of its supporting casing and is therefore provided with the relatively steep riffles 14 which extend 10 across the deck surface 15 at a slight inclination to the transverse axis of the deck, as will be apparent from Fig. 1, and the deck surface is supported at a transverse inclination, as clearly shown in Fig. 5. To this end 15 the deck structure is secured along one side thereof to the carriage or frame 10 by the hinges 16 and the opposite side of the deck is supported in spaced relation to the carriage 10 by the adjustable bolts 17, as will be apparent from Fig. 5.

The materials to be treated are delivered to the deck at the left-hand end thereof viewing Fig. 1 from the feed hopper 18 and as 20 the materials travel lengthwise of the deck under the influence of the longitudinal slope of the deck the concentrates will work along the riffles 14 towards the concentrate wall 19 at the upper side of the deck under the influence 25 of the progressive transverse vibratory movement which is imparted to the deck, as will be described. The lighter materials or tailings which tend to stratify above the concentrates will flow over the tops of the riffles 30 longitudinally of the deck and will gradually work downwardly towards the lower side thereof, to escape from the deck over the discharge board 20. The concentrates, upon 35 reaching the concentrate wall 19 will pile up against this wall and then fall back upon the riffles for further treatment in a well known manner.

It may be desirable to draw off the concentrates at a plurality of points lengthwise of the deck, and this may be accomplished by 40 providing the concentrate discharge gates 21 along the upper side of the deck, and which may be opened to permit the concentrates to escape from the deck into the concentrate discharge trough 22. This transversely vibratory deck is particularly well adapted for 45 treating relatively fine materials since the large number of riffles employed will afford ample opportunity for the concentrates and tailings to separate as they travel lengthwise of the deck. The very fine concentrates which arrive at the discharge end of the deck will enter the different discharge hoppers 23.

As above pointed out, one of the features of 50 the present invention resides in the novel construction of anti-friction bearings for supporting the frame or carriage 10 for vibratory movement relatively to its supporting structure. These anti-friction bearings are illustrated in the drawings as having the lower

ball receiving cups 24 which are secured to the supporting structure, and with the upper cups 25 which are secured to the under face of the carriage 10. Within the lower cup 24 is mounted a floor or bearing surface 26 which is preferably formed of rubber or other yielding, non-metallic material, and a bearing surface 27 of similar material is preferably provided in each upper cup 25. Each pair of cups 24, 25 is provided with an anti-friction ball 28.

It may be desirable to raise or lower the bearing to increase or decrease the weight supported by a particular bearing and this may be accomplished in the type of bearing 55 shown in Figs. 1, 5 and 9 by raising or lowering the floor or lower bearing plate 26, and to this end the lower cup 24 is provided with the adjusting bolt 29 which may be rotated to raise or lower the disk 30 upon which the 60 floor 26 rests.

Since the supporting structure upon which the frame 10 is mounted slopes downwardly in the direction of its length this inclination will tend to cause the anti-friction balls 28 65 to roll downwardly towards the lower sides of the bearing cups; this is undesirable and one form of means for preventing this displacement of the balls 28 from their central position is shown in Figs. 1, 5 and 9 wherein 70 it will be seen that the ball 28 is provided with the oppositely extending knobs or pins 31 adapted to enter recesses formed in the bearing blocks 26 and 27. The construction is such that these knobs or pins will retain 75 the balls 28 in their central position within the bearing cups while they will not interfere with the slight vibratory movement which is imparted to the frame 10.

It is desirable to exclude the dirt and dust 80 which commonly accompany separating operations from the anti-friction bearings and this may be done by providing each bearing with a sleeve 32 formed of rubber or other flexible material. The lower end of 85 this sleeve is tightly secured to the cup 24 by a binding wire or fastener 33 and the upper end of the sleeve is similarly secured to the 90 upper cup 25.

In the modified construction shown in Fig. 95 10 the centering pins or knobs of Fig. 9 have been omitted and the flexible sleeve is so constructed that it serves not only to exclude dust and dirt from the bearings, but also to retain the ball centrally 110 within its bearing cups. This is accomplished by forming the sleeve 34 of resilient material such as rubber, and by providing the ball 35 with an annular groove to which the central portion of the sleeve 34 is firmly 115 secured by the binding ring 36. The arrangement is such that the connection between the sleeve 34 and ball 35 will serve to maintain the ball centrally within the bearing 120 cups while the resilient sleeve will yield 125 130

sufficiently to accommodate the vibratory movement of the frame 10 supported by this anti-friction bearing. The object in forming the bearing blocks 26 and 27 of rubber or other non-metallic material is to provide 5 an anti-friction bearing which will operate smoothly and quietly and which will reduce to a minimum the wear between the anti-friction ball and the surfaces which engage the same.

10 Since the frame or carriage 10 slopes downwardly in the direction of its length it will obviously tend to move in a right-hand direction, viewing Fig. 1, under the influence 15 of gravity. This may be prevented by providing one or more anchoring cables 37 one end of which is secured to a bracket 38 fastened to the supporting structure and the other end of the cable is fastened to a bracket 20 39 extending downwardly from the under face of the carriage 10. Each cable 37 may be provided with the adjusting nuts 40 at either or both ends thereof to vary the effective length of the cables.

25 As above pointed out a further important feature of the present invention resides in novel means for imparting a transverse vibratory movement to the frame 10. This is accomplished, in accordance with the present invention, by providing the rocking levers 41 disposed near the opposite ends of 30 the supporting structure. Each of these levers is provided at its central portion with a downwardly extending stub shaft 42 which 35 is journaled in a bearing 43 that is rigidly secured to the supporting structure and in the lower bore of the bearing 43 may be provided an anti-friction ball 44 upon which the lower end of the stub shaft 42 may rest, the arrangement being such that the rocking levers 41 extend transversely of the supporting structure and are mounted thereupon for rocking movement. Each lever 41 is provided near its central portion with a lateral 40 projection 45 in which is mounted an upwardly extending stub shaft 46 which is adapted to extend into a bearing block 47 mounted upon the carriage 10. The arrangement is such that rocking movement of the lever 41 about its pivot pin or shaft 42 will rock the upwardly extending pin 46 through an angle to impart the desired transverse vibratory movement to the frame or carriage 10. In most constructions the vibratory movement employed will have a short stroke, say one-quarter of an inch, and as a result the pin 46 may be located relatively close to the pin 42 and it will be necessary to impart only a slight rocking movement to the levers 41. If desired the socket formed in the bearing block 47 to accommodate the upwardly extending pin 46 may be elongated 45 slightly lengthwise of the deck to better accommodate the arcuate movement of the pin 46.

Various means might be employed for rocking the levers 41 and the means shown to this end consists of cables which are secured to the opposite ends of the levers 41 to pull these levers back and forth. It is desirable that the levers 41 move back and forth in unison and the opposite ends of these levers are therefore connected, in the construction shown, by rods 48 the ends of which are adjustably secured to the blocks 48^a which are secured by pivot pins 48^b to the outer ends of the levers 41. In the construction shown, one connecting rod 48 is pulled in a right-hand direction viewing Fig. 4 by a cable 49 and is pulled in the left-hand direction by the cable 50; and the other connecting rod 48 is pulled in a right-hand direction by the cable 51, and in the left-hand direction by the cable 52. Each of these cables is looped about a grooved idle sheave 53 which is rotatably supported upon the main casing by a transversely extending shaft 54. These cables are pulled back and forth by the eccentrics 55 and 56 which are rigidly secured to the power shaft 57 and are disposed at 180° to each other as shown. The power shaft 57 may be rotated as usual by a pulley 58.

Upon the eccentrics 55 and 56 are journaled the sleeves or sheaves 59 and each of these sheaves is provided with a pair of cable receiving grooves, the arrangement being such that the cables 49 and 50 engage the grooves of one sheave 59 and the cables 51 and 52 engage the grooves of the other sheave 59. The cables 50 and 52 in the construction shown have their lower ends positively or non-yieldingly anchored to a transversely extending brace 60, and the lower ends of the cables 49 and 51 are yieldingly anchored to the transversely extending brace 61, this being accomplished by providing the bolts 62 which are fastened to the lower ends of the cables 49 and 51 with the coiled springs 63.

It will be apparent from the operating mechanism so far described that when the power shaft 57 is rotated the eccentrics 55 and 56 will move the sheaves 59 in an orbital path and this will serve to alternately tension and slack off the various cables described, with the result that the connecting rods 48 will be pulled back and forth to impart the desired rocking movement to the levers 41 to thereby move the deck back and forth transversely of its supporting structure. It is apparent that the levers 41 could be rocked back and forth by connecting only one end of each lever to the operating mechanism described, but through the present construction whereby the opposite ends of each lever are connected to the cable operating mechanism the levers are rocked back and forth with a smooth positive movement.

The operating mechanism so far described may impart a slight progressive vibratory movement to the deck as a result of the em-

ployment of the springs 63 which constitute yielding anchors for two of the cables, but this vibratory movement may not be as energetic as desired and it is therefore important to provide means for modifying the movement imparted to the deck so that the movement will be sufficiently energetic to advance the concentrates up the transversely inclined deck surface against the concentrate wall 19. This is accomplished, in accordance with the present invention, by providing the power shaft 57 with means for retarding the rotation of this shaft through part of a complete rotation and then speeding up the rotation of this shaft through a further part of its rotation. Simple and novel means to this end consists in the employment of an eccentric 64 which may have a greater throw than the eccentrics 55 and 56, and in the provision of yielding means adapted to cooperate with this eccentric to oppose its movement towards the yielding means.

One form of mechanism to this end is shown in Figs. 1 and 2 wherein the eccentric 64 is provided with a sleeve 65 journaled thereupon and over this sleeve is placed a strap or belt 66 the opposite ends of which are fastened to the yielding anchoring means best shown in Fig. 1. This anchoring means consists of a hub 67 mounted upon a central shaft 68 which is journaled in a bracket 69 fastened to a rail 12 of the supporting structure. To the hub 67 is rigidly secured one end of the yielding C-shaped member 70, the arrangement being such that the C-shaped member provides a smooth, curved bearing surface for the strap 66 which will yield as the tension upon the strap 66 varies. The end of the strap is anchored to the hub 67 by the pin 71. The tension of the strap 66 may be varied as desired by providing each hub 67 with a laterally extending arm 72 to which an adjusting bolt 73 may be secured by a pivot pin 74. The adjusting bolts 73 may extend towards each other, as will be apparent from Figs. 1 and 2, and their inner threaded ends may extend into the turn buckle 75 which may be rotated to produce the desired adjustment. These bolts 73 are supported for sliding movement by the brackets 76 which serve also to arrest the longitudinal movement of the turn buckle 75. The yielding anchored strap 66 will serve to retard the rotation of the shaft 57 as the eccentric 64 moves upwardly towards its vertical position, and as soon as this eccentric has moved past said vertical position, the rotation of the shaft 57 will be accelerated by the pull of the belt 66 downwardly upon the eccentric 64. This will serve to modify the speed at which the shaft 57 rotates and will impart the desired progressive vibratory movement to the vibratory frame 10.

Various forms of yielding means might be employed for opposing the movement of the eccentric 64 towards the yielding means and

a modified construction to this end is shown in Fig. 6 wherein the supporting structure of the concentrator is provided with an upwardly extending post 77 upon which is mounted a pneumatic bag or cushion 78 having the air valve 79 through which air may be introduced into the bag to inflate the same. This pneumatic bag will serve to vary the speed at which the shaft 57 rotates in a manner similar to the strap 66 above described.

Still a third form of means to this end is shown in Fig. 7 wherein a cable 80 is provided in place of the strap 66. This cable is looped over a grooved sheave 81 mounted upon the eccentric 64 and the opposite ends of this cable are provided with the springs 82 for yieldingly anchoring the ends of the cables to the supporting structure.

In some cases it may be desirable to vibrate the frame or carriage 10 diagonally of its supporting structure rather than transversely thereof as above described. This may be accomplished by providing the rocking levers 41 with upwardly extending stub shafts 46 which are disposed to one side of the central vertical plane of the pivot pins 42 of the rocking levers, as will be apparent from the modified construction shown in Fig. 8. In this modified construction the anchoring cable 87 is shown as having one end secured to the rocking shaft 41 at a point directly below the stub shaft 46, instead of being secured to a fixed bracket, as in the construction shown in Fig. 1.

What is claimed is:—

1. In combination with a supporting casing having a frame mounted thereupon for transverse vibratory movement, a pair of double ended levers pivotally mounted upon the supporting casing beneath the frame at points spaced lengthwise of the casing and each lever having a protruding portion intermediate its ends and constructed to impart the rocking movement of the lever to said frame, means connecting said levers to cause them to operate in unison, and power actuated means connected to the opposite ends of said levers to rock them to thereby impart transverse vibratory movement to said frame.

2. In combination with a supporting casing having a frame mounted thereupon for transverse vibratory movement, a pair of double ended levers pivotally mounted upon the supporting casing in spaced relation lengthwise thereof and each lever having a portion disposed intermediate its ends and constructed to impart the rocking movement of the lever to said frame, and power actuated means connected to the ends of the levers to rock them to thereby impart transverse vibratory movement to said frame.

3. In combination with a supporting casing having a frame mounted thereupon for transverse vibratory movement, a pair of double ended levers pivotally mounted upon the

supporting casing in spaced relation lengthwise thereof, each lever having an offset portion disposed intermediate its ends and a projection extending upwardly therefrom to actuate said frame, and power actuated means connected to the ends of the levers to rock them to thereby impart transverse vibratory movement to said frame.

4. In combination with a supporting casing having a frame mounted thereupon for transverse vibratory movement, a pair of levers pivotally mounted upon the supporting casing and each having oppositely extending arms and a lateral projection near said pivot, a connection between the lateral projection of each lever and said frame for imparting the rocking movement of the levers to the frame, and power actuated means connected to said arms to rock the levers and thereby 20 impart transverse vibratory movement to said frame.

5. In combination with a supporting casing having a frame mounted thereupon for transverse vibratory movement, a pair of levers pivotally mounted upon the supporting casing and each having oppositely extending arms and a lateral projection near said pivot, a connection between the lateral projection of each lever and said frame for imparting the 25 rocking movement of the levers to the frame, means connecting said arms to cause the levers to rock in unison, and power actuated means connected to said arms to rock the levers and thereby impart transverse vibratory 30 movement to said frame.

6. In combination with a supporting casing having a frame mounted thereupon for transverse vibratory movement, a pair of levers pivotally mounted upon the supporting casing and having oppositely extending arms and an offset portion near said pivot, a connection between the lateral projection of each lever and said frame for imparting the rocking movement of the levers to the frame, and 40 power actuated means connected to said arms and operable to rock the levers more energetically in one direction than the other to impart a progressive vibratory movement to said frame.

50 7. In combination with a supporting casing having a frame mounted thereupon for transverse vibratory movement, a pair of levers pivotally mounted upon the supporting casing and having oppositely extending arms and an offset portion near said pivot, connections between the offset portions of the levers and frame to actuate the latter, operating cables connected to said arms to rock said levers, and power means for tensioning and slackening off said cables.

8. In combination with a supporting casing having a frame mounted thereupon for transverse vibratory movement, a pair of levers pivotally mounted upon the supporting 60 casing and having oppositely extending arms

and an offset portion near said pivot, a projection extending upwardly from the offset portion of each lever into operative engagement with the frame to move the latter transversely of the casing as the levers are rocked, and power means acting through said arms to rock the levers.

9. In combination with a supporting casing having a frame mounted thereupon for vibratory movement, a power shaft, means actuated thereby to vibrate said frame, and means constructed to decrease the speed of rotation of said shaft through part of a complete rotation and to increase the speed of the shaft through another part of said rotation, comprising an eccentric rigidly secured to said shaft, and resilient means mounted to act against said eccentric to oppose its movement toward said means.

10. In combination with a supporting casing having a frame mounted thereupon for vibratory movement, a power shaft, means actuated by the power shaft to vibrate said frame, and means for decreasing the speed of rotation of said shaft through part of a complete rotation and for increasing it through another part of said rotation, comprising an eccentric rigidly secured to said shaft, a sleeve journaled upon the eccentric, and resilient means acting against said sleeve to oppose the movement of the eccentric toward said means.

11. In combination with a supporting casing having a frame mounted thereupon for vibratory movement, a power shaft, means actuated by the power shaft to vibrate said frame, and means for decreasing the speed of rotation of said shaft through part of a complete rotation and for increasing its speed during part of said rotation, comprising an eccentric, and a flexible member looped part way around said eccentric and yieldingly pulled thereagainst to oppose the movement of the eccentric toward the flexible member.

12. In combination with a supporting casing having a frame mounted thereupon for vibratory movement, a power shaft, means actuated by the power shaft to vibrate said frame, and means for decreasing the speed of rotation of said shaft through part of a complete rotation and for increasing its speed during part of said rotation, comprising an eccentric, a sleeve journaled upon the eccentric, and a strap yieldingly held against the sleeve to oppose the movement of the eccentric in the strap tensioning direction.

13. In combination with a supporting casing having a frame mounted thereupon for vibratory movement, a power shaft, means actuated by the power shaft to vibrate said frame, and means for decreasing the speed of rotation of said shaft through part of a complete rotation and for increasing its speed during part of said rotation, comprising an eccentric, a sleeve journaled upon the eccentric, a strap embracing said sleeve, and re-

silient anchoring means for the ends of said strap and adapted to force the strap against the sleeve to oppose the movement of the eccentric in the strap tensioning direction.

14. In combination with a supporting casing having a frame mounted thereupon for vibratory movement, a power shaft, means actuated by the power shaft to vibrate said frame, and means for decreasing and then increasing the speed of rotation of said shaft during a complete revolution, comprising an eccentric, a sleeve journaled upon the eccentric, a strap embracing said sleeve, spring anchoring means for the ends of the strap and operable to resist the rotation of the eccentric toward the strap, and adjustable means for varying the tension of the anchoring springs.

15. In combination with a supporting casing having a frame mounted thereupon for vibratory movement, a power shaft, means actuated by the power shaft to vibrate said frame, and means for decreasing and then increasing the speed of rotation of said shaft during a complete revolution, comprising an eccentric, a sleeve journaled upon the eccentric, a strap embracing said sleeve, and a C-shaped tensioning spring anchored at one end only and arranged to provide an extended strap tensioning surface adapted to pull the strap against the sleeve to oppose the movement of the eccentric toward the strap.

In testimony whereof, I have signed my name to this specification.
